UNITED STATES PATENT OFFICE

149,231

DESIGN FOR A STORE FRONT

Nathan Sharaf, Brookline, Mass.

Application February 13, 1946, Serial No. 126,537

Term of patent 14 years

(Cl. D13—1)

To all whom it may concern:

Be it known that I, Nathan Sharaf, a citizen of the United States, residing at Brookline, in the county of Norfolk and State of Massachusetts, have invented a new, original, and ornamental Design for a Store Front, of which the following is a specification, reference being had to the accompanying drawings, forming a part thereof, in which:

I claim:

The ornamental design for a store front, as shown.

NATHAN SHARAF.
